UNITED STATES PATENT OFFICE.

OZELLO R. HUNT, OF KENOSHA, WISCONSIN, ASSIGNOR TO THE SIMMONS MANUFACTURING COMPANY, OF KENOSHA, WISCONSIN, A CORPORATION OF WISCONSIN.

LEAF-SUPPORT FOR SOFA-BEDS.

SPECIFICATION forming part of Letters Patent No. 754,142, dated March 8, 1904.

Application filed September 17, 1902. Serial No. 128,703. (No model.)

To all whom it may concern:

Be it known that I, OZELLO R. HUNT, a citizen of the United States, residing at Kenosha, in the county of Kenosha and State of Wisconsin, have invented a new and useful Improvement 5 in Leaf-Supports for Sofa-Beds, &c., of which the following is a specification.

My invention relates particularly to automatically-released leaf-supports for the rear leaves or backs of sofa-beds.

My primary object is to provide a leaf-support of this character of exceedingly simple and durable construction and perfectly reliable in operation.

15 In the accompanying drawings my invention is illustrated in connection with a main frame and rear leaf or back of a sofa-bed, though it will be obvious that the invention may be applied to other articles of furniture 20 of a similar nature.

In the drawings, Figure 1 represents a broken view in side elevation of a sofa-bed equipped with my improvement; Fig. 2, a broken vertical section looking at the inside 25 of the end frame shown in Fig. 1; and Fig. 3, a broken plan section, taken as indicated at line 3 of Fig. 2.

In the preferred construction, A' represents an end standard of the main frame of a sofa- 30 bed; B, a wire fabric applied to the seat and back of the sofa-bed; C, a back or rear leaf of the sofa-bed; D, a link pivotally connected at one end with the back C and provided at its free end with a stud D', and E a spring 35 which serves in the locking and releasing of the free end of the link. It will be understood that ordinarily each end of the sofa-bed is provided with this equipment. Assuming the leaf C to be in the standing position shown in 40 Fig. 1, the link D has pivotal connection with the leaf at a point b some distance above the pivot b' of the leaf. The link has a substantially vertical portion c, a forwardly-curved portion c, and an upwardly and forwardly ex- 45 tending portion c', which bears the stud D'. The end standard A' is provided at its horizontal member with a horizontal slot F, having an enlargement or offset F' at its front

upper portion, affording a stationary locking-shoulder F², corresponding with the standing 50 position of the leaf, the front end of the slot serving as a stationary locking-shoulder F³, corresponding with the horizontal position of the leaf. The spring E is connected by rivets d with the horizontal member of the end stand- 55 ard and has an inclined portion d', which crosses the slot F and its enlargement F' in the manner shown in Fig. 2, the rear extremity of the spring being curved downwardly, preferably, as shown. Said spring is pro- 60 vided with a recess or slot d'', located opposite the front portion of the offset F'. The stud D' is headed on its outer end and extends through the slot F and inwardly a short dis- 65 tance beyond the outer edge of the spring E. Preferably the rear vertical member of the end standard of the frame is an angle-iron and has its inturned flange provided with a slot f, serving as a guide for the link D.

The operation will be readily understood. 70 In the standing position of the leaf the spring E serves to hold the front extremity of the link D in an elevated position, thereby caus- 75 ing the stud D' to engage the shoulder F². This prevents the back or leaf from dropping, 80 as is evident. When it is desired to release the back and lower it to the horizontal position, the back is moved forwardly somewhat from the position shown in Fig. 1 till the stud D' enters the slot d'' of the spring and per- 85 mits the link to fall, whereupon the leaf is lowered, the stud during this movement riding upon the lower wall of the slot and forcing the spring upwardly until it is cleared by the stud. When the leaf reaches the hor- 90 95 izontal position, the stud engages the rear end of the slot, as indicated by dotted lines in Fig. 1. When the leaf is again raised to the standing position, the inner extremity of the stud D' rides upon the upper surface of the extremity of the spring and is forced to the locking position shown in full lines.

While my invention was devised for use in the situation illustrated, it is evident that it may be employed in analogous situations. 95 For instance, it may be employed to connect

the back to the seat-frame of a sofa-bed, regardless of whether or not the seat-frame is fixed immovably to its supports or standards. Moreover, it will be understood that the arrangement of the parts may be altered or reversed without departure from my invention.

Changes in details of construction within the spirit of the appended claims may be made. Hence no undue limitation should be understood from the foregoing detailed description.

What I regard as new, and desire to secure by Letters Patent, is—

1. In an article of the character described, the combination of a main frame provided with a guide and a stationary locking-shoulder, of a swinging leaf connected with said main frame, a link connected with said leaf and provided at its free end with a stud engaging said shoulder, and a yielding member with means for holding said stud in engagement with said shoulder in one position of the leaf and permitting said stud to drop automatically and clear said shoulder in another position of the leaf, for the purpose set forth.
2. In an article of the character described, the combination of a main frame provided with a guide and two locking-shoulders corresponding with different positions of the back, of a swinging back connected with said main frame, a link connected with said back and provided at its free end with a stud serving to engage either one of said shoulders, according to the position of the back, and a yielding device with means for holding said stud in engagement with one of said shoulders in one position of the leaf and permitting the link to drop automatically in another position of the leaf, so that the leaf can be moved so as to bring said stud into engagement with the other shoulder.
3. In an article of the character described, the combination of a main frame provided with a guide and a locking-shoulder corresponding with the standing position of the back and a locking-shoulder in the rear of said first-named locking-shoulder corresponding with the horizontal position of the back, a swinging back, a link connected with said back and provided at its free end with a stud engaging said guide, and a spring serving to hold said stud in engagement with the front locking-shoulder in the standing position of said back and to permit said stud to drop out of engagement with said shoulder when said back is moved in front of its normal standing position, the guide then serving to direct the stud into engagement with the rear shoulder, for the purpose set forth.
4. In an article of the character described, the combination of a main frame provided with a guide-slot having an offset at its upper

front portion, whereby a locking-shoulder is presented at the rear portion of said offset, and another locking-shoulder at the rear end 65 of said slot, a swinging leaf, a link connected with said leaf and provided at its free end with a stud engaging said slot, a spring serving to direct said stud to said front locking-shoulder and hold it in engagement therewith, 70 said spring having a recess, and a stud on said link riding on said spring until said recess is reached, for the purpose set forth.

5. In an article of the character described, the combination of a main frame provided 75 with a guide-slot presenting two locking-shoulders corresponding with two positions of the swinging leaf, a swinging leaf connected with said main frame, a link connected with said leaf and provided at its front end 80 with a stud engaging said slot, a spring secured at its front end to said main frame, and provided with a recess, the rear portion of said spring extending across said slot, and a stud on said link which rides upon the rear 85 portion of the spring till said recess is reached, for the purpose set forth.

6. The combination of two frame members hinged to swing with relation to each other, one of said members having a guide and a 90 locking-shoulder corresponding with the angular position of the members with relation to each other, a link carried by the other member and equipped with a locking-lug, and a yielding member with means for automatically forcing said lug into engagement with said shoulder in one relative position of said first-named members and permitting said lug to fall clear of said shoulder and effect an automatic release in another relative position of 95 said first-named members, for the purpose set forth.

7. The combination of two frame members hinged to swing with relation to each other, one of said frame members having a guide 105 and locking-shoulder, a link connected with the other frame member and equipped at its free end with a stud engaging said guide, and a spring attached to the guide-equipped frame member and crossing said guide and having 110 a portion serving to lift said stud into engagement with said shoulder during one movement of the swinging frame member and permit said stud to fall during a supplemental movement of the swinging frame member to 115 pass beneath said spring during the return movement of the swinging frame member whereby an automatic locking and releasing of the swinging frame member is secured, for the purpose set forth.

OZELLO R. HUNT.

In presence of—

A. C. KITTLESON,
ALBERT S. BACCI.
